UNITED STATES PATENT OFFICE.

WALTER W. SCOTT, OF AMSTERDAM, NEW YORK, ASSIGNOR TO UNION SPECIAL MACHINE COMPANY, OF CHICAGO, ILLINOIS, A CORPORATION OF ILLINOIS.

SEWING MACHINE.

Application filed July 11, 1918. Serial No. 244,262.

To all whom it may concern:

Be it known that I, WALTER W. SCOTT, a citizen of the United States, residing at Amsterdam, in the county of Montgomery, State 5 of New York, have invented certain new and useful Improvements in Sewing Machines, of which the following is a description, reference being had to the accompanying drawing and to the figures of reference marked 10 thereon.

The invention relates to new and useful improvements in sewing machines, and more particularly to a sewing machine having means for guiding, shaping and stitching a 15 collarette to a garment.

The object of the invention is to provide a sewing machine having guiding devices for guiding a collarette strip, which guiding devices are so constructed and positioned relative to the stitching mechanism that they 20 may be shifted by the operator at will and when so shifted the feed of the machine drawing the collarette strip through said guiding devices will cause the gradual shifting of the collarette strip at the trimming 25 point, so as to taper the strip.

In the drawings—

Figure 1 is a front view of a sewing machine having my improved guiding devices 30 applied thereto;

Figure 1^a is a view parallel with the line of feed, showing the feed dogs, the presser foot and the strip guide;

Figure 2 is a view, partly in section and 35 partly in top plan, showing the work support, presser foot, trimming devices and the guiding devices for the collarette strip;

Figure 3 is a view in plan, showing the presser foot and the guiding devices, with the 40 guiding devices shifted causing the collarette strip to be tapered at the finishing end thereof;

Figure 4 is a view similar to Figure 3, but 45 after the feed has drawn the strip through the guiding device in its new position a sufficient distance to finish the tapering of the collarette;

Figure 5 is a front view of a portion of the machine, showing my improved guiding device in full lines positioned for the beginning and the finishing of the tapering of the collarette strip, and in dotted line position 50 for directing the collarette strip between said operations;

Figure 6 is a perspective view of my improved collarette strip guiding devices removed from the machine;

Figure 7 is a view showing more or less diagrammatically the throat plate, presser foot, trimming devices, with the collarette 60 strip positioned during the stitching between garments;

Figure 8 is a similar view, but showing the collarette strip when positioned for stitching the full width of the strip;

Figure 9 is a view showing the throat plate, the needles and the position of the collarette in the body fabric as it is stitched by the needles;

Figure 10 is a view showing more or less 70 diagrammatically, the finishing of one garment, the beginning of another garment and the connecting lines of stitching between the garments;

Figure 11 is a sectional view on the line 75 11—11 of Figure 10;

Figure 12 is a sectional view on the line 12—12 of Figure 10;

Figure 13 is a sectional view on the line 80 13—13 of Figure 10; and

Figure 14 represents the upper portion of a finished garment, having the collarette applied according to my invention.

My invention is particularly adapted for the shaping of a collarette strip at the ends 85 thereof and the stitching of the same to a body garment. In Figure 12 of the drawings I have shown a garment at G, to which a strip, indicated at S, has been stitched. It will be noted that this collarette strip at each 90 end is tapered from about the points a to b. This collarette strip is secured to the garment by stitches, indicated at B. These stitches, as herein shown, are covering stitches and are preferably formed by two 95 spaced needles with a cooperating thread laying member above the material which covers the edges of the collarette strip and a looper which cooperates with both needles below the material and the looper thread 100 covers the edge of the body fabric. In Figures 11 to 13 of the drawings, I have shown the needle threads of my preferred form of stitching mechanism at n—n, the upper covering thread at c and the lower looper thread 105 at l.

The sewing machine to which my invention has been applied consists of a work

- support 1, a bed plate 2, carrying the work support, and an overhanging arm 3 mounted on the bed plate. Reciprocating at the forward end of the overhanging arm is a needle bar 4, carrying two needles 5 and 6. The needle bar is reciprocated by a needle lever 7, which is connected to an eccentric strap 8, cooperating with an eccentric on the main shaft 9.
- 10 The covering thread *c* is led through a fixed guide 10 and an oscillating hook 11 engages this covering thread *c* and lays the same in loop form so that it is stitched down by the needle threads. A looper of the ordinary construction cooperates with the needles beneath the work support and carries the looper thread *l*. The material is held on the work support by a presser foot 12, carried by a presser bar 13, which may be of the usual construction. Said presser foot is formed with a guiding slot 14, which extends from the extreme forward end thereof rearwardly in the line of feed. The presser foot has a needle opening 15 through which the needles pass.
- 15 The machine includes a trimming mechanism having horizontally disposed trimming blades. One of these blades is indicated at 15. This blade is stationary and is fixed to the presser foot 12. Cooperating with this fixed blade is a movable blade 16. These blades are so disposed as to trim the upturned edges of the fabric sections directed into the guiding slot 14. The collarette strip passing underneath the presser foot has its edges turned up, so as to be brought into the range of this trimming mechanism. Afterwards they are brought back into the plane of the fabric sections 20 and stitched, as above noted, by the stitching mechanism, which includes the needles 5 and 6, the cross thread laying mechanism and the looper co-operating therewith.
- 25 The body portion of the garment *G* passes underneath the presser foot, and is guided by a lip 17, mounted on the throat plate 18 and extending upwardly therefrom. This lip is curved to the left slightly, as viewed in Figures 7 and 8, and serves to direct or upturn the edges of the collarette strip to bring them into the range of the trimming devices. The body fabric is preferably passed through the machine without trimming as the neck of the garment is usually shaped ready for the attachment of the collarette strip thereto. The collarette strip *S* is directed to the stitching mechanism by guiding devices, which include a tubular guide 19, which is carried by a bracket 20, and the bracket 20 is in turn clamped to the work support 1 by means of the clamping screw 21. The tubular guide 19 is secured to the lower end of an arm 22, which is pivoted at 23 to the bracket 20. The lower end of this arm is bent laterally, as indicated at 24, and the tubular guide 19 is soldered or otherwise connected to this lateral portion 24. The upper end of the arm 22 is bent laterally, as indicated at 25, which serves as a handle for shifting the arm 22. 70 Mounted on the bracket 20 is an adjustable stop 26 and also an adjustable stop 27. The arm 25 may be moved within certain limits determined by these adjustable stops 26 and 27. The pivoted connection between the 75 arm and the bracket is of such a character as to vertically hold the arm in adjusted position against either stop.
- 80 The material is fed underneath the presser foot by a feeding mechanism which includes feed dogs 28, which may be of the usual construction and operated by any suitable mechanism. These feed dogs are preferably given a differential feeding movement. The feed dogs operate both upon the body fabric 85 and the collarette strip and draw the same underneath the presser foot.
- 85 When the parts are positioned, as shown in full lines in Figures 1 and 2, the collarette strip passing underneath the presser foot 90 will be directed so that only a small portion of the edges will be trimmed off and the line of trimming will be substantially parallel with the edges of the strip. When the guiding devices are positioned, as shown in Figure 3, then the tubular guide is arranged relative to the stitching mechanism, so that the folded edge of the collarette strip and not the free edges will be substantially in line with the trimming point, so that while 95 the machine is operated and the guide maintained in this position the line of cutting will be close to the folded edge in the strip and parallel therewith—leaving just enough of the strip so as to maintain control on the 100 strip and feed the same underneath the presser foot while passing from one garment to another. When the guide is shifted from the position in Figure 2 to the position in Figure 3, the strip leading from the tubular 110 guide 19 will take a new position of lead into the machine. Inasmuch as this strip is clamped by the presser foot, a number of stitches will be made and a number of feed steps will take place before the collarette 115 strip will pass directly to the trimming members from the tubular guide 19. As a result the line of trimming will follow the curved line between *a* and *b*, indicated in Figures 10 and 14 of the drawings. The reason for this is thought to be apparent. The operator shifts the guide by hand and at will, and it is the feed of the machine drawing the strip in underneath the presser foot, with this new position of the guide, which 120 causes the tapering of the collarette strip.
- 125 In the beginning of the collarette stitching operation, the guide 19 is set, as viewed in Figures 3 and 4. The strip passes underneath the presser foot and the line of cut- 130

ting is parallel with the folded edge and close thereto. The resulting action of the stitching mechanism and trimmer on the collarette strip is indicated in Figure 11 of the drawings wherein it will be noted that a small portion of the collarette strip is passing through the machine underneath the presser foot which strip is substantially encircled by the stitches. It is desirable at this time to have just enough of the collarette strip passing underneath the foot as to continue to pull the strip underneath the foot. The operator then places the body garment on the work support and just before the edge *g* (see Figure 10) reaches the needles the guide is shifted by hand quickly to the full line position shown in Figures 1 and 2. By the term "quickly" I desire to define a movement wherein the guide is shifted from one extreme position to the other without stopping as distinguished from a step by step movement which covers necessarily a considerable period of time. The feed draws the strip underneath the presser foot and the strip at once begins to shift gradually to take up this new position of lead in under the foot. As a result the line of trimming gradually shifts away from the folded edge of the collarette strip and in the curved line *b-a*, as viewed in the lower part of Figure 10. This produces a gradual tapering of the collarette strip. The stitching proceeds after the point *a* is reached and the strip is then of its normal width until the point is reached where it is desired to taper and finish the end of the collarette strip to correspond to the beginning end thereof. Let us assume that this position is at the point *a* at the upper part of Figure 10. When this point is reached, the operator quickly shifts the guide 19 to the position shown in Figure 3. The feed continues to draw the strip underneath the foot and the strip gradually assumes its new position of lead in underneath the foot and as a result the line of trimming is from *a* to *b*, as indicated at the upper part of Figure 10.

It will be noted that the guide is shifted at will by the operator and the time at which the tapering of the strip begins is, therefore, controlled by the operator. No matter what size the neck of the garment may be, the operator, when the desired point is reached, shifts the guide and the tapering of the collarette occurs. On the other hand, when passing between garments, no matter how long a time occurs, the operator can always begin the tapering of the strip at the right point for attachment to the garment. It will also be noted that, while the operator shifts the guide to bring about the tapering of the collarette, the tapering is not brought about by any step by step movement of the guide, but by a quick shifting

of the guide, which possibly occurs during the formation of a single stitch and the feed of the machine rather than any step by step shifting of the guide determines the character of the taper at the ends of the collarette.

It will be obvious that minor changes in the details of construction and arrangement of parts may be made without departing from the spirit of the invention, as set forth in the appended claims.

Having thus described my invention, what I claim as new and desire to secure by Letters Patent, is:

1. The combination with a sewing machine having stitching mechanism, feeding mechanism and a trimming mechanism operating in advance of the stitching mechanism, of a strip guide for directing a strip to the trimming mechanism and stitching mechanism, and means for supporting said guide whereby it may be shifted quickly with the strip carried thereby and at the will of the operator transversely of the line of feed from one extreme guiding position to another, said guide being disposed a sufficient distance in advance of the trimming mechanism so that the strip may be swung to permit said shifting of the guide and the shifting of the guide to cause the strip as it is fed through the machine to be tapered.

2. The combination with a sewing machine having stitching mechanism, feeding mechanism and a trimming mechanism operating in advance of the stitching mechanism, of a strip guide for directing a strip to the trimming mechanism and stitching mechanism, and means for supporting said guide whereby it may be shifted quickly with the strip carried thereby and at the will of the operator transversely of the line of feed from one extreme guiding position to another, said guide being disposed a sufficient distance in advance of the trimming mechanism so that the strip may be swung to permit said shifting of the guide and the shifting of the guide to cause the strip as it is fed through the machine to be tapered, said supporting means including a bracket, means for movably supporting the guide on said bracket, and stops for limiting the movement of the guide.

3. The combination with a sewing machine having stitching mechanism, feeding mechanism and a trimming mechanism operating in advance of the stitching mechanism, of a strip guide for directing a strip to the trimming mechanism and stitching mechanism, means for supporting said guide whereby it may be shifted quickly transversely of the line of feed from one extreme guiding position to another, said guide being disposed a sufficient distance in advance of the trimming mechanism so that the strip may be swung to permit said shifting of the

guide, said supporting means including a bracket, an arm pivoted to the bracket, and adjustable stops for limiting the movement of the arm.

5 4. The combination with a sewing machine having stitching mechanism, feeding mechanism and horizontally disposed trimming members operating in advance of the stitching mechanism, of a strip guide for 10 directing a strip to the trimming members and the stitching mechanism, means for supporting the said guide whereby it may be shifted quickly with the strip carried thereby and transversely of the line of feed from 15 one extreme guiding position to another, said guide being disposed a sufficient distance in advance of the trimming members so that the strip may be swung to permit said shifting of the guide and the shifting 20 of the guide to cause the strip as it is fed through the machine to be tapered.

5. The combination with a sewing machine having stitching mechanism, feeding mechanism and horizontally disposed trimming members operating in advance of the stitching mechanism, of a strip guide for 25 directing a strip to the trimming members and the stitching mechanism, means for supporting the said guide whereby it may be shifted quickly with the strip carried thereby and transversely of the line of feed from 30 one extreme guiding position to another, said guide being disposed a sufficient distance in advance of the trimming members 35 so that the strip may be swung to permit said shifting of the guide, said supporting means including a bracket, an arm pivoted to the bracket and carrying said guide, and stops for limiting the movement of the arm.

40 6. The combination with a sewing machine having stitching mechanism, feeding mechanism and horizontally disposed trimming members operating in advance of the stitching mechanism, of a strip guide for 45 directing a strip to the trimming members and the stitching mechanism, means for supporting said strip guide whereby the same may be shifted quickly with the strip carried thereby and from a position where one 50 edge of the strip is adjacent the trimming line to a position where the other edge of the strip is adjacent the trimming line, said trimming line in both positions of the guide being within the strip.

55 7. The combination in a sewing machine, of stitching mechanism for forming parallel lines of connected stitches, feeding mechanism, a presser foot having a guiding channel extending from the front end of the 60 presser foot rearwardly in the line of feed,

horizontally disposed trimming members operating across the guiding channel, means for turning up the edges of the folded fabric strip, whereby they are presented to the trimming members, the guide located in 65 front of the presser foot for guiding a folded strip to the trimming members, and means for supporting the guide whereby it may be shifted quickly transversely of the line of feed from one extreme guiding position to 70 another extreme guiding position for shifting the trimming line relative to the strip but within the limits of the strip.

8. The combination in a sewing machine, of stitching mechanism for forming parallel 75 lines of connected stitches, feeding mechanism, a presser foot having a guiding channel extending from the front end of the presser foot rearwardly in the line of feed, horizontally disposed trimming members operating across the guiding channel, means for turning up the edges of the folded fabric strip, whereby they are presented to the trimming members, means for guiding a body garment to the stitching mechanism 80 whereby the edge thereof passes between the needles, and means for guiding a folded collarette strip to the trimming members, said last named means including devices which may be shifted at will from one extreme 85 guiding position to another and in a direction relative to the presser foot, so as to vary the extent to which the edges of the folded strip are raised above the horizontal trimming members, whereby the collarette 90 strip attached to the body garment may be tapered at each end of the collarette.

9. The combination in a sewing machine, of a stitching mechanism for forming parallel lines of connected stitches, horizontally 100 disposed trimming members in advance of the stitching mechanism, means for guiding a body garment with the edge thereof between the lines of stitching, means for guiding a folded collarette strip to the trimming members and the trimmed edges between the lines of stitching, said last named means including a shiftable guide controlled at will by the operator and disposed relative to the trimming members and movable relative 105 thereto, whereby the collarette strip may be trimmed so as to taper the ends of the collarette as it is stitched to the body garment.

In testimony whereof, I affix my signature, in the presence of two witnesses.

WALTER W. SCOTT.
